GOLF BAG

Florence H. Lace and William P. Lace, Bronx,
N. Y.; said Florence H. Lace assignor to said
William P. Lace

Application May 9, 1952, Serial No. 286,874

2 Claims. (Cl. 150—1.5)

1

This invention relates to a golfer's bag, and has for its principal object the construction of a golf bag which will be compact and easily carried; which will accommodate a large variety of different clubs and other paraphernalia necessary to the golfer; which will be self-supporting so as to hold the various clubs within convenient reach of the golfer; and in which the heads of the clubs will be protected from damaging engagement with each other and from the inclemencies of the weather.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view of the improved golf bag in the open, ready-to-use position;

Fig. 2 is a vertical section therethrough, taken on the line 2—2, Fig. 3; and

Fig. 3 is a horizontal cross-section, taken on the line 3—3, Fig. 2.

The improved golf bag is reinforced with and supported by a light, metallic, vertically elongated, supporting frame 10 having a rectangular cross-section. The frame 10 is covered on the exterior by means of panels of any suitable material, such as veneered ply board, fiber, plastic, fabric, or leather, to form a front panel 11, two side panels 12, and a back panel 13. The panels 11, 12, and 13 are integral or permanently joined at the four vertical corners to provide a permanent, substantially rectangular, enclosing case.

The bottom of the case is closed by means of a suitable bottom panel 14 having upturned flanged edges which form a protecting band 15 about the bottom of the case. The upper extremities of the side panels 12 are first inclined forwardly and downwardly from the top of the back panel 13 to form gradually inclined upper edges 16 which terminate at their forward extremities in relatively steep, inclined front upper edges 17 which terminate above the upper extremity of the front panel 11.

Three inclined partition members 18, 19, and 20 extend transversally across the case between the two side panels 12. The front partition member 18 extends from the top of the front panel 11 downwardly and rearwardly to an attachment

2

21 with the bottom 14 of the case. The rear partition member 20 extends from a point substantially mid-way between the front and back panels 11 and 13, and from a height above the front panel 11 rearwardly and downwardly to an attachment 22 with the bottom 14 adjacent the rear edge of the latter. The intermediate partition member 19 is placed parallel to the partition members 18 and 20 and substantially mid-way therebetween, and extends rearwardly and downwardly from a point above the top of the front partition member 18 and below the top of the rear partition member 20. The lower extremity of the intermediate partition member 19 is turned rearwardly to an attachment 23 with the rear partition member 20 to form an elevated sub-bottom 24.

A flexible, depending curtain 25 is suspended across between the junctures of the upper edges 16 and 17 of the side panels 12 and extends rearwardly to the upper extremity of the rear partition member 20. Two compartment curtains 26 intersect each other at right angles rearwardly of the curtain 25 to outline four wood-club compartments 27. The curtains 25 and 26 are supported from suitable cross members 47 supported by the supporting frame 10.

The frame 10 supports the entire case with sufficient rigidity so that it will stand upright without support. In use, the handles of the wood clubs are inserted into the compartments 27 and slid down the rear face of the partition member 20 to rest upon the bottom 14. The heads of the clubs will be maintained separated and protected by the flexible curtains 25 and 26.

The handles of the longer iron clubs are slid downwardly between the partition members 19 and 20 to rest upon the sub-bottom 24, and the handles of the shorter iron clubs are slid downwardly between the two partition members 18 and 19 to rest upon the bottom panel 14. It will be noted that all of the clubs are within the view and reach of the golfer.

When not in use, the clubs can be securely enclosed by means of a weather-tight cover flap 28. The flap is formed from any suitable flexible, weather-resisting material, and is stitched or otherwise secured along the upper edge of the back panel 13. When not in use, the flap 28 extends rearwardly and downwardly along the back panel 13 and is secured by means of a suitable fastener 29. The flap is closed by releasing it from the fastener 29, folding it forwardly over the top of the case, and securing it along the

3

edges by means of a suitable slide fastener of the "zipper" type, as indicated at 30.

Two auxiliary pockets 31 and 32 are stitched, stapled, riveted, or otherwise fastened to the forward face of the forward partition member 18. These pockets are accessible through a flexible door 33 closed by a second slide fastener 34, which is protected by a concealing flap 35. The pockets 31 and 32 form convenient repositories for the golf tees and extra balls.

Since the forward partition 18 is set back from the front of the bottom panel 14, it forms a very convenient storage compartment 36 which is accessible through a door flap 37 secured by a third slide fastener 38 and protected by a flap 39. The compartment 36 forms a very convenient place for carrying that pair of the golfer's shoes which is not in use. A separate, vertically-elongated, open-topped compartment is provided in the compartment 36 extending completely to the top of the front panel 11 and designed as an umbrella compartment 40.

A flexible side pocket 41 is mounted on the exterior of one of the side panels 12 for carrying extra articles of clothing and for carrying a protecting cover which can be used to completely enclose the improved golf bag while shipping or storing. Access to the side pocket 41 may be had through a triangular, flexible flap 42 closed by means of a fourth slide fastener 43.

The bag may be provided with the usual detachable shoulder strap 44 and carrying handle 45, and is suitably ventilated to evaporate moisture by means of ventilation passages 46.

While a specific form of the improvement has been described and illustrated herein, it is desired to be understood that the same may be varied, within the scope of the appended claims, without departing from the spirit of the invention.

4

Having thus described the invention, what is claimed and desired secured by Letters Patent is:

1. A golfer's bag comprising: a vertically elongated case closed at its front, rear, and sides and having a closed bottom; a plurality of inclined partition members extending from side to side in said case and inclining from a position adjacent the front of said case near the top thereof to a position adjacent the rear of said case at the bottom thereof, the rearmost partition member cooperating with the rear of said case to form a multiple club compartment having less width at the bottom than at the top; and curtain members supported at the top of said multiple compartment and intersecting each other to form individual club entrances into the top of said multiple club compartment, said curtain members extending downwardly but a short distance into said multiple compartment.
2. A golfer's bag as described in claim 1 having a cross curtain extending transversally across the upper portion of said case and terminating at its bottom on the top of the rearmost partition member.
